STEPHEN D. SHOBE AND FLOYD L. KOHN, OF GLENMORE, OHIO.

ELECTRICALLY-OPERATED PHONOGRAPH.

Application filed June 25, 1923. Serial No. 647,575.

To all whom it may concern:

Be it known that we, STEPHEN D. SHOBE and FLOYD L. KOHN, both citizens of the United States, and residents of Glenmore, in the county of Van Wert and State of Ohio, have invented a new and useful Improvement in Electrically-Operated Phonographs, of which the following is a full, clear, and exact description.

10 Our invention relates to improvements in electrically operated phonographs, and it consists in the combinations, constructions, and arrangements herein described and claimed.

15 An object of our invention is to provide an electrically operated phonograph of the character described in which an electric motor is employed for actuating the device and in which means is provided for automatically disconnecting the electric motor when the record has been completed.

20 A further object of our invention is to provide an electrically operated phonograph of the character described which employs a minimum amount of gears for transmitting power to the record plate of the electric motor and therefore greatly decreases the motor sounds which conflict with the tones and music reproduced from the record.

25 30 A further object of our invention is to provide an electrically operated phonograph of the character described which may be operated from the ordinary electric lighting circuit.

35 A further object of our invention is to provide an electrically operated phonograph of the character described which is simple in construction, durable, and thoroughly efficient for the purpose intended.

40 Other objects and advantages will appear in the following specification, and the novel features of the invention will be particularly pointed out in the appended claims.

Our invention is illustrated in the accompanying drawings, forming part of this application, in which

Figure 1 is a sectional view of an embodiment of our invention,

Figure 2 is an enlarged view, partly in section, of the automatic switch, and

Figure 3 is a sectional view along the line 3—3 of Figure 1.

In carrying out our invention, we make use of the ordinary phonograph instrument

having a horizontal board 1 beneath which the mechanism for actuating a record plate 2 is placed. The record plate 2 is placed upon a rotatably mounted shaft 3 and is disposed upon the upper side of the panel 1 so that the phonograph record may be placed upon the plate and caused to revolve in a horizontal plane when the shaft 3 is turned. The shaft 3 is provided with a worm wheel 4. A second shaft 5, having a worm gear 6 at its outer end in mesh with the worm wheel 4, is disposed in a plane transverse to the plane of the shaft 3, and a governor mechanism 7 is carried by the shaft 5. The governor mechanism 7 is further provided with a plate 8.

A felt shoe 9, carried at one end of a pivotally mounted L-shaped lever 10, is arranged to normally engage with the plate 8 so that movement of the lever 10 on its pivotal support 11 may occasion the plate 8 to move longitudinally of the shaft 5 and thereby limit the expansion of the governor 6 and hence the speed of the shaft 5.

A compression spring 12 serves to normally hold a lever 10 in the position shown in full lines in Figure 1.

Means for moving the lever 10 against the action of the compression spring 12 is provided in a threaded rod 13 projected through a threaded plate 14 carried by the panel 1. A knob 15 is provided at the upper end of a screw 13, by means of which the screw can be turned to cause the movement of the lever 10 on its pivotal support 11.

The shaft 5 has a pulley wheel 16 mounted thereon and a belt 17 is employed to connect the pulley wheel 16 with the pulley wheel 18 of an electric motor 19. This motor 19 is of a fractional horse power type and ordinarily noiseless in operation.

A transformer 20 is mounted in the compartment adjacent the motor 19 and has its primary windings 21 arranged for connection with the house lighting circuit or current source 22. This current source is preferably 110 volts and the current is alternating.

The secondary winding 23 of the transformer is of substantially 60 volts and one terminal 24 thereof is connected directly with one lead wire 25 of the motor 19 by means of a conductor 26. The terminal 24 is also connected by means of the conductor

26^a to a stationary contact member 27 disposed adjacent the base 28 of the tone arm 29 of the phonograph (see Figure 3).

An ordinary socket switch 30 of the push and pull type having a toggle operated switch, is mounted on the panel 1 so that the base 28 thereof projects above the panel and one terminal 32 of the switch is connected by means of a conductor 33 to the opposite terminal 34 of the motor 19. This switch 30 is provided with a vertically extending stem 35 by means of which the switch may be operated. In Figure 2 we have shown the switch in closed position so that current may flow through the switch. A magnet coil 36 of the ordinary type, such as is employed in an enunciator, or the like, is mounted adjacent the switch 30 and one terminal 37 of the coil is connected to the opposite terminal 38 of the switch 30. The opposite terminal 39 of the magnet coil 36 is connected by means of a conductor 40 with an annular band 41 disposed concentric the tone arm 29 and securely clamped thereto. The band 41 is further provided with an outwardly extending contact member 42 electrically connected therewith which may contact with the contact member 27 when the tone arm has been moved to the position shown in dotted lines in Figure 3, as when the needle of the reproducer has reached the end of the record.

A pivotally mounted lever 43 is supported adjacent the magnet coil 36 and an arm 44 is carried by the lower end of the lever 43 in registration with the core 45 of the magnet coil 36. The upper end of the lever 43 has a bar 46 thereon.

A switch operating lever 47 is pivotally supported at 48 so that one end 49 thereof may engage with the bar 46 of the lever 43 in such a manner as to prevent the movement in one direction of the lever 47, while the lever 43 is in the position shown in Figure 2, i. e., when the arm 44 is out of close engagement with the core 45 of the coil 46.

The compression spring 50 is employed for normally holding the end 49 of the lever 47 away from the panel 1.

The opposite end 51 of the lever 47 is disposed directly above the head 52 of the stem 35 of the switch 30.

From the foregoing description of the various parts of the device, the operation thereof may be readily understood. In operating our improved electrically actuated phonograph, it is necessary first to manually move the switch 35 to the position shown in Figure 2. This will cause the circuit to close and current will flow from the secondary winding of the transformer 20 through the motor, through the conductor 33, the switch 30, and back by way of a conductor 53 to the opposite terminal 54 of the secondary winding 23 of the trans-

former. This will cause the motor 19 to operate and to turn the shaft 5, which in turn will actuate the shaft 3 and cause the record plate 2 to rotate, carrying the record therewith, and sound will be reproduced from the reproducer which is carried by the tone arm 29 in precisely the same manner as in the ordinary type of spring actuated phonograph. The governor 7 will function also in precisely the same manner as the ordinary type of governor employed in the spring actuated phonograph. Variation in speed of the shaft 5 may be obtained by a rotation of the rod 13 which will cause the shoe 9 of the lever 10 to move toward or away from the plate 9, depending upon the direction in which the rod 13 is rotated.

When the needle in the reproducer has reached the inner end of the recording groove of the record, the tone arm 29 is moved upon its pivotal support (it is of ordinary construction to have the tone arm pivot upon its supporting base 28) and as the tone arm 29 moves, the contact member 42 contacts with the contact member 27 at the moment the record has been completed. This will cause current to flow from the secondary winding 23 of the transformer through the conductor 26^a, through the contact members 27—42, by way of the conductor 40 through the magnet coil 36, and back to the opposite terminal of the secondary winding 23 of the transformer by way of the conductor 53. Since the circuit in which the magnet coil 36 is employed is now complete, the magnet coil will become energized and cause the lever 46 to move out of engagement with the lever 47. The spring 50 will therefore cause the lever 47 to be forcefully projected in an upward direction. As a consequence, the opposite end 51 of the lever 47 will be forcefully projected in a downward direction and will cause the stem 45 of the switch 30 to be pushed inwardly and therefore actuate the toggle switch 41 to break the connection between the terminals 32 and 38 of the switch. This will cause the motor 19 to be disconnected from the secondary winding of the transformer and rotation of the plate 2 will cease.

It will be noted that one of the important advantages of our electrically actuated phonograph is that there are no mechanical springs and also no heavy springs to wind after each record has been played.

We claim:

1. In a device of the character described, a manually operated switch, a pivotally mounted lever, one end arranged to overlie the handle portion of said switch, a spring disposed at the opposite end of said lever and arranged to cause said lever to bear against said switch handle, a trigger for holding said lever out of engagement with

said switch handle against the action of said spring, and electrically operated means for releasing said trigger, whereby said lever may engage with said switch handle and manipulate said switch.

2. The combination with a rotatably mounted record supporting plate, a pivotally mounted tone arm adjacent to said plate, of an electric motor arranged to rotate said plate, an electric circuit for operating said motor, a switch disposed in said circuit and capable of manual manipulation, a pivotally mounted lever, one end arranged to overlie the handle portion of said

switch, a spring disposed at the opposite 15 end of said lever and arranged to cause said lever to bear against said switch handle, a trigger for holding said lever out of engagement with said switch handle against the action of said spring, and electrically 20 operated means associated with said tone arm for releasing said trigger when said tone arm is in a predetermined position, whereby said lever may engage with said switch handle and manipulate said switch.
